UNITED STATES PATENT OFFICE

ANTHONY J. STOUGES, OF QUEENS VILLAGE, NEW YORK, ASSIGNOR TO
MERGENTHALER LINOTYPE COMPANY, A CORPORATION OF NEW YORK

TYPOGRAPHICAL MACHINE

Application filed July 8, 1931. Serial No. 549,371.

This invention relates to slug casting machines and is directed to improved means for handling matrix lines composed in hand sticks, the improvements being especially 5 adapted to slug casting machines such as shown in my pending application, Serial No. 545,398. In this machine, the composed lines (which may comprise either regular linotype matrices formed with projecting ears or 10 larger special matrices devoid of projecting ears) are delivered to a vertically movable transporter which is then caused to descend to present the lines to the molds and which later, after the slug casting operation, is returned 15 to its original receiving position for the removal of the lines.

The present improvements include a manually operated carriage for transferring the matrix lines from the hand composing sticks 20 into the transporter, a table arranged adjacent the receiving end of the transporter for supporting the sticks at the transfer level, and a device for locating the individual sticks on the table in operative relation to the transfer carriage and the transporter.

The composing sticks employed are of two different lengths and are especially constructed to cooperate with the carriage in effecting the transfer of the composed lines. 30 The short sticks are used for the composition of matrix lines of the minimum length (preferably 42 ems) and such as are adapted for ordinary text matter or to certain classes of advertising work, whereas the long sticks are 35 used for the composition of matrix lines of greater lengths and such as are adapted to headlines, streamers, titles, and other classes of advertising work.

The end walls of the short sticks, which 40 afford abutments for the opposite ends of the matrix lines, are adapted to be displaced automatically as the individual sticks are moved into operative relation to the transfer carriage, so that the matrix lines may be transferred from the sticks into the transporter without requiring any further attention on 45 the part of the operator.

In the use of the long sticks, it is proposed to separate the individual composed matrix 50 lines into sections of the given minimum

length (in this instance 42 ems) and to transfer the sections consecutively from the stick to the transporter. To this end, each long stick is provided with one or more partition plates, which divide it into separate compartments 55 and which together with one end wall of the stick (that serving the first compartment) are also adapted to be displaced automatically as the stick is placed in the line transfer position. In the course of composition, the 60 partition plates will occupy their displaced or inactive position, but after the line has been completely composed, the plates are moved to active position to divide the line into the individual sections as above referred 65 to.

In transferring the composed line from the stick, the first section, by means of the stick locating device, is positioned between the fingers of the transfer carriage and shifted 70 thereby from the stick into the transporter. While the transporter is presenting the line section to the mold, the transfer carriage is returned to its original receiving position, 75 and the next or second section of the line is then shifted endwise into the vacant first compartment of the stick where it is likewise positioned between the fingers of the carriage for transfer into the transporter.

When the transporter finally comes to rest 80 in its upper or normal position, the first section of the matrix line is removed therefrom, and this operation in the present instance is effected automatically as the second section 85 of the line is delivered thereto. In the preferred embodiment illustrated, the removing means consists of a finger or pusher mounted on the transfer carriage and arranged in advance of the line section positioned therein for transfer. The matrix line sections removed from the transporter are deposited in a suitable receptacle disposed at the level of the table but arranged adjacent the opposite end of the transporter.

These and other features will be fully set 90 forth in the detailed description to follow.

In the accompanying drawings, the invention has been shown merely in preferred form and by way of example and as applied to a 100 particular slug casting machine, but obvi-

ously many changes and variations may be made therein and in its mode of application, which will still be comprised within its spirit. It should, therefore, be understood that the invention is not limited to any specific form or embodiment, except insofar as such limitations are specified in the appended claims.

Referring to the drawings:

Fig. 1 is a front view of the upper portion 10 of a slug casting machine equipped with the present improvements;

Fig. 2 is an enlarged side elevation, partly 15 in section, showing the transporter supported on the vise frame at the proper level to locate a line of regular matrices in the casting position;

Fig. 3 is an enlarged front view, partly in 20 section and broken away, of the improved transfer mechanism showing a short composing stick clamped in the transfer position;

Fig. 4 is a top plan view, partly in section, 25 of the parts shown in Fig. 3, illustrating by the full and dotted lines, respectively, a short composing stick in position on the table before and after it is alined with the transporter;

Fig. 5 is a vertical section taken on the line 5—5 of Fig. 3;

Fig. 6 is a similar section taken on the line 30 6—6 of Fig. 3;

Fig. 7 is a detail section taken on the line 35 7—7 of Fig. 3, showing the manner of supporting the regular and special matrices in their passage through the intermediate channel;

Fig. 8 is a full size detail horizontal section, 40 partly in elevation, showing the alining devices for the sticks and the releasing devices for the blank matrices;

Fig. 9 is a vertical section taken on the line 45 9—9 of Fig. 8;

Figs. 10 and 11 are detail perspective views 50 of a special blank matrix and a regular blank matrix, respectively;

Figs. 12, 13, and 14 are plan views, on a small scale, illustrating the mode of handling 55 the two sections of a line composed in one of the long sticks before and after the casting operations;

Fig. 15 is a detail perspective view of one 60 of the special matrices;

Fig. 16 is a face view of four special upper 65 case matrices representative of as many different fonts and indicating the base alinement of the respective characters;

Fig. 17 is a detail perspective view of a regular single letter display matrix;

Fig. 18 is a face view of two regular two-letter 70 matrices and a regular display single letter matrix, showing them in the relative positions they occupy for casting;

Fig. 19 is a perspective view of one of the short composing sticks;

Fig. 20 is a top plan view of one of the

long composing sticks having two compartments;

Fig. 21 is a side view of the stick shown in Fig. 20;

Fig. 22 is a vertical section taken on the 70 line 22—22 of Fig. 20; and

Fig. 23 is a similar section taken on the line 23—23 of Fig. 20.

This disc A (see Figs. 1 and 2) is rotatably mounted as usual on the fore-and-aft mold 75 slide (not shown) and is equipped with four slotted molds, any selected one of which may be brought into use by the rotary adjustment of the disc A by the manual operation of the driving pinion A². As the machine 80 is started by operating the handle 7, which controls the main driving clutch, the cam shaft is rotated slowly, and the mold disc or carrier A is given a quarter turn in an anti-clockwise direction (looking from the front 85 of the machine) to locate the selected mold in the casting position. The elevator or transporter B then descends to position a line of matrices (previously delivered thereto) in front of the active mold, where the line is 90 justified between the clamping jaws, C¹, C², mounted in the fixed vertically disposed vise frame D. The mold slide is now moved forward to bring the active mold up against the matrix line, which thereby closes the mold 95 slot at the front, and the metal pot is likewise advanced from its normal position behind the disc A to bring the mouthpiece thereof up against the back of the mold, thereby closing the mold slot at the rear. The 100 descent of the pot plungers immediately follows, and molten metal is ejected from the pot into the mold to produce the slug. After the casting operation, the pot and mold are caused to recede, the transporter is raised, and the active mold is carried to the slug 105 ejecting position. As the machine completes its cycle of operation, the slug is ejected from the mold and the transporter B is finally arrested at its original or uppermost level. 110

The several molds may include two of the usual height or depth and of regular construction to cooperate with the regular matrices Y, Y¹, and two of less than the usual height or depth and of special construction 115 to cooperate with the special matrices X. The regular matrices Y and Y¹ (see Figs. 17 and 18) are formed with the upper projecting ears y⁴ and the lower projecting ears y². The matrices Y are provided with two superposed characters y³ and confined to the smaller text fonts ranging below 14 pt., while the matrices Y¹ are provided with but a single character y⁴ and confined to the larger head-letter and display fonts above 14 pt. 120 The characters of the regular matrix fonts are positioned as usual, and for reasons well-known, with reference to a common datum line for top alinement; whereas the characters x of the special fonts, 125

130

and which have a range up to 72 pt. in height, are positioned (as shown in Fig. 16) with reference to the common datum line $a-a$ for base alinement, so that the matrices may be mixed indiscriminately in the same line, irrespective of the height of their individual characters. The special matrices X are formed on their bottom edges with alining surfaces x^1 and in their casting edges with recesses or routing notches x^2 , which are preferably of a depth to compensate for the reduced depth of the special molds. At their upper ends, the matrices X are provided with corresponding open notches x^3, x^4 formed in their front and rear edges respectively and with intermediate lugs or extensions x^5 .

Blank matrices X^1 (Fig. 10), similar in form to the special matrices X but devoid of the recesses x^2 , are used, one at each end of a composed line, to prevent metal squirts through said recesses during casting; and blank matrices Y^2 (Fig. 11), similar in form to the regular matrices Y, Y^1 , are used in like manner but serve merely as filler pieces to bring the composed lines to the proper length.

The line transporter B (Figs. 1 and 2) comprises the elongated vertically disposed body portion B^1 slidably mounted in the fixed vise frame D , the top flange B^2 which overhangs said frame, and the horizontally disposed head portion B^3 which depends from the rear edge of the flange B^2 . The head portion B^3 , wherein the matrix lines are sustained, consists of the front and rear side walls B^4 and B^5 and the intermediate spacing block B^6 arranged at one end of the head (see Fig. 2). The front wall B^4 is provided near the bottom with the horizontal supporting ledge b and about midway of its height with an opposed shoulder b^1 located directly opposite the lower edge of the rear side wall B^5 . The arrangement of these parts is such that, when the special matrices X are supported on the ledge b , the lower edge of the wall B^5 and the shoulder b^1 of the front wall B^4 will fit or snugly engage the front and rear notches x^3, x^4 in the upper ends of the matrices and by means of the lugs x^5 sustain them in upright position.

When the matrices Y or Y^1 are in use, an auxiliary back plate B^7 (Fig. 2) is attached to the rear wall B^5 of the transporter, the lower edge of said plate being extended below said wall so as to engage the upper projecting ears of these matrices and thus sustain them in upright position on the ledge b is adapted to support either the matrices Y or Y^1 at the normal lower casting level, and the corresponding ledge b^6 , which is located directly above the ledge b , is adapted to support the two-letter matrices Y at the normal upper casting level.

So far described, the parts, their construction, and mode of operation are or may be the same as those embodied in the machine dis-

closed in the pending application before mentioned and in themselves constitute no part of the present invention, the later, as previously stated, being devoted to means for handling the composed matrix lines before and after each slug casting operation.

In Fig. 19, there is shown a short hand composing stick J , which has but one compartment J^1 and comprises a bottom wall J^2 , one side wall J^3 integral with and rising from the front edge of the bottom wall (assuming the stick to occupy the position shown in Fig. 4), and two end walls J^4, J^5 which form abutments for the opposite ends of a composed line. The end walls J^4 and J^5 , as will be noted (see Figs. 8 and 9), are pivotally mounted in vertical cuts or notches J^6 formed in the side wall J^3 so that they may be rocked edgewise back and forth into and out of active or line retaining position, the respective pivot pins j thereof being located immediately adjacent the bottom wall J^2 .

The pivotal movement of these end walls is reduced to a minimum by making them triangular in form; thus, their lower inclined edges j^1 in the normal position of the walls extend diagonally upward from the pivot pins j across the ends of the stick, and their outer straight edges j^2, j^3 conform to the rectangular outline thereof (see Fig. 19). Consequently, by swinging the walls J^4, J^5 forwardly through an arc of forty-five degrees, they will be located completely out of the path of the matrix line with their inclined edges j^1 in registry with the inner face of the fixed side wall J^3 . Ball detents j^4 , mounted in the stick and engaging corresponding shallow recesses j^5 formed in the outer side faces of the end walls J^4, J^5 , hold the latter against accidental displacement and maintain them yieldingly in their different positions.

While the side wall J^3 of the stick is adequate in itself to support and guide the end walls J^4, J^5 during their pivotal movements, additional side support is required when they occupy their normal or active position. For this reason, the stick is provided with a pair of upright corner members J^7, J^8 , which rise from the rear edge of the bottom wall J^2 and which, as best shown in Fig. 19, are formed with open slots or bifurcations J^9 alined with the slots J^6 of the side wall J^3 and wherein the free ends or nose portions j^6 of the end walls engage. The nose portions j^6 , as may be observed, are adapted to project somewhat beyond the upright members J^7, J^8 , in the normal or active position of the walls J^4, J^5 and are formed with curved cam surfaces j^7 by which the said walls may be swung to their inactive position (see Fig. 9). The member J^8 at the right (according to Fig. 4) is formed with a lateral extension J^{10} abutting against the front wall J^3 , to which it is fastened, and serving to reinforce that

end of the stick; whereas, the member J^7 at the left has no such extension, being spaced from the wall J^3 so as to leave the stick open at that end.

- 5 The distance between the inner faces of the two end walls J^4 , J^5 (as shown) is 46 ems, space being allowed for a pair of blank matrices X^1 or Y^2 , of two ems thickness each, to be used at the opposite ends of a composed 70
10 42 em line. For reasons later to appear, the blank matrices employed are anchored in the stick by hook-shaped detents j^8 slidably mounted in the bottom wall J^2 and extending across the stick from front to rear (see 75
15 Fig. 8). The shank portions of the detents j^8 terminate flush with the rear edge of the bottom wall J^2 , and the curved or active portions thereof engage in circular apertures x^6 , y^6 formed in the blank matrices X^1 , Y^2 , 80
20 respectively. The detents j^8 are held resiliently in locking position by flat springs j^9 secured in shallow recesses j^{10} formed in the outer face of the front wall J^3 .

In adapting the stick J to the regular 25
25 matrices Y , Y^1 , as well as to the special matrices X , and in order that both kinds may be properly supported therein with their front edges fitting against the side wall J^3 , the inner face of said wall at the top is formed with 30
30 a longitudinal clearance recess j^{11} for the upper projecting ears of the regular matrices Y or Y^1 and at the bottom is formed with a pair of longitudinal clearance grooves j^{12} for the lower projecting ears of said matrices. 35
35 The rib or ledge j^{13} intermediate the grooves j^{12} is adapted to support the two-letter matrices Y when they are composed at the upper or auxiliary level. In this connection, it may also be observed that the lower inclined edge 40
40 of the end wall J^4 is shaped to correspond to the irregular inner face of the side wall J^3 , so that it will register accurately therewith at all points when the wall J^4 is moved to inactive position (Fig. 9). A smooth uninterrupted guiding surface for the front edges of 45
45 the matrices is, therefore, insured as they pass through the open end of the stick J .

To prevent a line of matrices from being 50
50 dislodged or falling out of the stick J , the latter is provided with a clamping screw J^{11} , the latter (as best shown in Fig. 3) being mounted transversely in the extension J^{10} of the upright member J^8 at a point which allows it to clear the end wall J^5 . The screw 55
55 J^{11} cooperates directly with the blank matrix X^1 or Y^2 at that end of the matrix line; and to permit the slight facewise movement required, the apertures x^6 or y^6 in the blank matrices at the opposite ends of the line are made purposely larger than the diameter of the hook detents j^8 .

The number of matrices necessary to make 60
60 up a completely composed matrix line is determined by means of an ordinary graduated scale J^{12} , which is secured to the bottom wall 65
65

J^2 of the stick J between the upright members J^7 , J^8 .

The long stick K , (see Figs. 20 to 23, inclusive) corresponds in many respects, both in form and construction, to the short stick J 70
75 above described. That is to say, the stick K (see Fig. 20) comprises generally a continuous flat bottom wall K^3 , a side wall K^4 rising at one edge from the bottom wall, upright members K^5 , K^6 , K^7 , rising from the opposite edge thereof, and two end walls K^8 , K^9 . In addition to the elements recited, however, the stick K is provided with an intermediate partition plate K^{10} , which divides it into the two 80
85 separate compartments K^1 and K^2 of equal length. The first compartment K^1 , like the single compartment J^1 of the stick J , is open at one side (opposite the side wall K^4); whereas, the second compartment K^2 is closed 85
90 partially at that side by a low wall K^{11} . The stick K is also adapted to handle both regular and special matrices, the side wall K^4 being formed in its inner face at the top with a longitudinal clearance notch or recess k for the upper projecting ears y^1 of the matrices 90
95 Y , Y^1 , and at the bottom with two parallel grooves k^1 and an intermediate supporting ledge k^2 , which cooperate with the lower projecting ears y^2 of said matrices.

The end wall K^8 at the left (Fig. 20) and the partition plate K^{10} are similar in shape to the end walls J^4 , J^5 of the stick J , and both are mounted to swing about individual axes k^3 located within the side wall K^4 at points adjacent the bottom wall K^3 . As shown, the partition plate K^{10} is mounted in a separate block K^{12} , which is embedded in and fastened to the side wall K^4 , but such construction is merely for purposes of manufacture and does not effect the general arrangement of the parts. The end wall K^8 and the partition plate K^{10} , as in the case of the end walls J^4 and J^5 of the stick J , receive the required side support in their normal or active position (Figs. 22 and 23) by the associated upright members K^5 and K^6 respectively, both of which are bifurcated or slotted to engage the nose portions k^4 of the said end wall and partition plate.

The opposite end wall K^9 of the stick K is in the form of a flat rectangular plate, rigidly secured to the other upright member K^7 , and also to both the bottom and side walls K^3 , K^4 . An aperture or finger hole k^5 cut through the end wall K^9 permits the adjacent section of the composed line to be pushed endwise and advanced sufficiently to facilitate its transfer to the first compartment K^1 .

The length of each compartment K^1 , K^2 , from the partition plate K^{10} to the opposite end wall K^8 or K^9 , is 46 ems, allowance being made for positioning two blank matrices X^1 or Y^2 , of 2 ems thickness each, at the opposite ends of each compartment. The stick K , however, is devoid of the anchoring detents 125
130

j^8 or similar devices, so that the blank matrices X^1 or Y^2 after casting may be discharged from the transporter with the individual sections of the matrix line.

5 The stick K (see Fig. 20) is equipped with two short 42 em scales K^{13} , one for each of the two compartments K^1 , K^2 , and also with a longer 84 em scale K^{14} , which extends substantially throughout the length of the stick 10 and which is utilized during composition of the matrix line.

15 The improved transfer mechanism (see Figs. 3, 5, 6 and 7) includes a reciprocable carriage F mounted to slide in horizontal angular guideways G, supported at the right of the transporter B in stand-brackets G^1 , G^2 upon a table H, and which extend to the left beyond the table directly above the transporter head B^3 (see Fig. 1). The guideways 20 G (Fig. 5) present a front upper wall G^3 formed with a longitudinal groove g , and a lower rear supporting flange G^4 engaged in open recesses or notches g^1 formed in the tops of the brackets G^1 , G^2 . In the present instance, the guideways G, for reasons of safety, 25 are capable of yielding upwardly from their normal positions, being hingedly mounted (as best shown in Figs. 3 and 6) on a cross-pin g^2 in the right-hand bracket G^2 , and supported in a truly horizontal position, by seating of the flange G^4 in the notch g^1 of the left-hand bracket G^1 . The bracket G^2 (see 30 Figs. 4 and 6) is provided at points immediately above the table H with a banking screw O and a stud P, for purposes presently to be described.

35 The carriage F comprises, generally, a main horizontal bar F^1 , a pair of retaining gibs F^2 , F^3 , and intermediate anti-friction rollers f^1 , f^2 , by which it is supported and maintained in the guideways G. The bar F^1 (see Figs. 40 5 and 6) fits against the rear face of the wall G^3 of the guideways, and the gibs F^2 , F^3 , which are fastened at their upper ends to the 45 bar F^1 , fit against the front face of said wall. The rollers f^1 are arranged to track upon the top surface of the wall G^3 , and the rollers f^2 are arranged in the longitudinal groove g . The carriage F is operable by a vertical handle F^4 rising from one end of the bar F^1 , and by which it may be shifted manually to and fro in the guideways G to transfer matrix lines from the stick J or K to a definite position in the transporter B. The reciprocal 50 movements of the carriage F are limited by a pair of stop screws g^3 , g^4 mounted in the guideways G at the opposite ends thereof, the stop screw g^3 at the left being disposed in the path of the gib F^2 of the carriage, and the stop screw g^4 at the right being disposed in the path of the corresponding gib F^3 .

55 The carriage F is also provided with a pair of depending line engaging fingers F^5 , F^6 , which are spaced a given distance apart and adapted to enter the transporter between the

side walls B^4 , B^5 . The left-hand finger F^5 is integral with the gib F^2 of the carriage F; whereas the right-hand finger F^6 , for reasons later to be pointed out, is slidably mounted in the gib F^3 so that it may be raised and lowered as desired. When in active position, the finger F^6 is firmly supported and held in place by a keeper plate F^7 fastened to the front face of the gib F^3 . The gibs themselves are also rigidly connected to each other by means of a tie rod F^8 to insure the stability required. The finger F^6 is manipulated by a cross-pin f^9 mounted in its upper end which terminates slightly above the carriage F. This cross-pin serves also to limit the downward movement of the finger by its engagement with the upper edge of the keeper plate F^7 (see Fig. 3). The distance between the fingers F^5 , F^6 (see Figs. 4 and 12) corresponds to the distance 70 between the end walls of the stick J and also to the distance between the movable end walls of the first compartment in the stick K (as constituted by the wall K^8 and partition plate K^{10}), so that the said end walls will be rocked forwardly out of the path of the matrix line by the engagement of their nose portions j^6 or k^4 with the transfer fingers, when the individual sticks are moved rearwardly on the table H into operative relation to the carriage. 75

80 The carriage F, as may also be noted (see Figs. 3 and 5), is further provided with a third finger F^9 , which is formed at the lower end of a depending angular bracket arm F^{10} fastened to the rear face of the main supporting bar F^1 . The finger F^9 (Fig. 4) is aligned with the transfer fingers F^5 , F^6 , but is arranged at a considerable distance in advance of the left-hand finger F^5 , so that it will be caused to pass from a position immediately adjacent the receiving end of the head B^3 completely through and slightly beyond the same at each active stroke of the carriage F. Consequently, a matrix line supported in the transporter at such time will be ejected therefrom by the finger F^9 , as another is delivered thereto from the stick J or K.

85 100 To receive the ejected matrices, there is employed a suitable receptacle in the form of a stick T which, as best shown in Fig. 1, is 105 mounted for removal upon a platform T^1 disposed at the level of the table H at the opposite side of the transporter B. The stick T (see Fig. 12) is aligned with the transporter head B^3 and is held against displacement in a shallow cut or groove t formed in the top surface of the platform T^1 . The platform T^1 is supported by means of a center post or pedestal T^2 , which is permanently mounted in the machine frame (see Fig. 1).

110 115 In passing from the stick J or K during the transfer operation, the individual matrices of a composed line are guided into the transporter B by a short intermediate channel L (see Figs. 3, 4, and 7) which is mounted on the 120 125

70

table H and which comprises, mainly, a front wall L¹ provided with an inner matrix supporting ledge l corresponding to and adapted to aline with the upper ledge b⁶ of the transporter; a bottom wall L² equal in thickness to the bottom walls of the sticks and which is adapted to aline with the lower ledge b of the transporter; and a rear side wall L³ secured by screws L⁴ to the fixed stand-bracket G¹.
 5 The rear side wall L³ (see Fig. 4) is extended at the left slightly beyond the table H so as to register with the auxiliary back plate B⁷ when the latter is attached to the head of the transporter B. A beveled fillet block L⁵ is fastened to the table directly beneath the overhang portion of said wall L³ to obviate possible interferences at this point. Above the block L⁵ (see Fig. 3), the wall L³ is formed with a notch L⁶, which provides clearance for
 10 the lower end portion of the arm F¹⁰ when the transfer carriage F occupies its normal position. The upper wall of the notch L⁶ (see Fig. 4) is formed at one end of a separate horizontal plate L⁷, which is pivotally mounted at its opposite end on a screw L⁸ and arranged in a recess L⁹, flush with the front face of the rear side wall L³. The plate L⁷ merely constitutes a movable section of the wall L³ and thus permits the upward swinging of the guide-ways and carriage, irrespective of the arm F¹⁰, in the manner before stated.
 15
 20
 25
 30
 35
 40
 45
 50
 55

The side wall L³ (see Fig. 4) is also formed at the right with an extension L¹⁰, which is offset rearwardly from the front face of the wall and provided about midway of its width with a vertical rib L¹¹. The extension L¹⁰ is further provided with a banking screw O¹ and a stud P¹ arranged near the lower edge thereof and which correspond respectively to the banking screw O and the stud P of the stand-bracket G². The banking screws O and O¹ are relied upon to aline the sticks J or K with the head B³ of the transporter and the intermediate channel L, while the studs P and P¹ are arranged to cooperate with the hook-shaped detents j⁸ of the stick J so as to release the blank matrices X¹ or Y² at the opposite ends of the composed line when the stick is pushed against the said banking screws. In this connection, it may be noted by reference to Fig. 23 that the stick K, being devoid of such detents j⁸, is provided with clearance holes p in the rear edge of its bottom wall K³, to avoid interference with the studs P and P¹ when these particular sticks are alined with the transporter B.

The improved transfer mechanism also includes a device R for locating the sticks J and K endwise upon the table H and which is operable to guide them into the proper position against the banking screws O and O¹. The locating device R (see Figs. 3 and 4) comprises a body portion R¹ mounted to slide back and forth in a rigid block R² arranged between the stand-brackets G¹, G²

upon the table H. The body portion R¹ is provided with a horizontal cross-bar R³ secured by screws and dowels r to the front edge thereof, and which presents a flat vertical face r¹ adapted to fit against the matrix lines supported in the sticks J and K, the lower edge of said bar R³ being spaced above the table H to allow the bottom wall of the stick in use to be passed beneath it. In length, the cross-bar R³ corresponds to the horizontal distance between the upright members J⁷, J⁸ of the stick J and also to that between the corresponding upright members K⁵, K⁶ located at the opposite ends of the first compartment in the stick K. In other words, the cross-bar R³ is adapted to fit between these members of the respective sticks when it is positioned against the matrix line, and will thus locate either the stick J or K in a definite position on the table H. In this way, the movable end walls J⁴, J⁵ of the stick J or the movable end wall K⁸ and partition plate K¹⁰ of the stick K are brought directly opposite the transfer fingers F⁵, F⁶ of the carriage F, and will be displaced thereby in the manner before described when the stick is pushed rearwardly against the banking screws O, O¹. At the same time, the matrix line is properly positioned between the transfer fingers F⁵, F⁶, and the stick properly alined with the transporter B and the intermediate channel L.

If the short stick J is in use, the detents j⁸ by their engagement with the studs P, P¹ will be pushed forwardly to release the blank matrices X¹, Y² and will thus free the line for transfer. The aforementioned vertical rib L¹¹, associated with the channel L, serves merely as a filler piece for either the stick J or K and is adapted when the sticks are alined against the banking screws O, O¹ to enter the bifurcations of the upright members J⁷ or K⁶ so that a continuous unbroken guiding surface, which is formed mainly by the plate R³, will be presented to the rear edges of the matrices in the line to insure their passage uninterruptedly from the stick into the channel L.

Additional means are provided for holding the individual sticks J and K against the banking screws O, O¹ during the line transfer operations. Such means (see Figs. 3 and 6) consist of a rotary segmental wedge M fixed to the inner end of a fore-and-aft-rock shaft M¹ journaled beneath the table H in bearing lugs M². The rock shaft M¹ is provided at its outer end with a knurled knob or operating handle M³ arranged conveniently at the front of the table and whereby the wedge M may be turned to active or inactive position. The wedge M operates in a clearance aperture H¹ formed in the table and is held resiliently out of action against a lug m (see dotted lines, Fig. 3) by a spring M⁴ coiled about the shaft M¹. At such times, the

wedge M is located entirely below the top surface of the table H so that the sticks may be moved back and forth with the desired freedom to and from the transfer position. 5 At other times, i. e., when the wedge is turned to active position, its outer edge is projected above the table so as to engage and clamp the stick in place. If desired, each of the sticks J and K may be provided with a wear 10 shoe or stud m¹ to cooperate with the wedge and which projects slightly beyond the outer surfaces of their respective side walls J³ and K⁴.

The operation of the parts is as follows: 15 Assuming the machine to be at rest and a short stick J to have been clamped in the transfer position against the stops O, O¹ (as shown in Fig. 3), the matrix line (including the blank matrices X¹ or Y² at the opposite 20 ends thereof) may be transferred through the intermediate channel L and into the transporter B by shifting the carriage F in the guideways G toward the left until it is arrested in the position indicated by the 25 dotted lines, Fig. 1, by the engagement of the gib G² with the stop g³. The machine may now be started by operating the control handle 7, which brings about the descent of the transporter and the casting of the slug. 30 As the cycle of operation is completed and the transporter restored to the transfer level, the matrix line therein will be repositioned between the fingers F⁵, F⁶ and may thereupon be shifted back into the stick J by the return 35 stroke of the transfer carriage F, the stop screw g⁴ serving to arrest the carriage in its original position (Fig. 3). In removing the stick J from the machine after it has been unlocked by a partial turn of the wedge M, 40 it is merely necessary to grasp the stick and locating plate R³, slide them forwardly from beneath the carriage, and finally swing the end walls J⁴, J⁵ over into their active position, the hook detents j⁶ during the forward movement of the stick being allowed, by action of 45 their control springs j⁹, to reengage the blank end matrices X¹ or Y² and anchor them in the stick. Handling of these blank matrices during composition is thus avoided and considerable time is saved as a result.

The procedure above described is desirable in instances where the job is small and but few lines are required, but when the work involved is more extensive and time is a factor, 55 several sticks J may be employed, each being removed from the machine and replaced by another as soon as the line is transferred therefrom into the transporter; and the carriage being returned to its normal position 60 immediately after the transporter descends. Under these latter conditions, therefore, and subsequent to each casting operation, a matrix line will be positioned in the transporter and another positioned in a stick between the 65 fingers F⁵, F⁶ ready for transfer. Thus,

when the carriage F is operated to deliver one matrix line to the transporter, the finger F⁹ of the carriage is adapted to push the other out of the transporter and deposit it in the receptacle T. 70

Figs. 12, 13, and 14 illustrate the different steps followed in the handling of the individual sections of a matrix line composed in the long stick K. The stick K is first located by means of the device R in the position indicated by the dotted lines in Fig. 12, with its first compartment K¹ directly opposite the carriage F, and the stick is then pushed rearwardly to position the leading section of the matrix line between the transfer fingers F⁵, F⁶. 75 After the stick is locked by the wedge M against the banking screws O, O¹, the said line section is delivered to the transporter by an active stroke of the carriage F. As soon as the transporter descends, the carriage is returned to its normal position and the transfer fingers F⁵, F⁶ thereof are located at the opposite ends of the vacant compartment K¹. The right-hand finger F⁶ is now raised 80 by means of the cross-pin f³ to the position indicated by the dotted lines in Fig. 3, so that the other or following section of the composed line may be shifted endwise by hand into the compartment K¹ and up against the left-hand finger F⁵ (see Fig. 13). The right-hand finger F⁶ is then lowered to engage the matrix line section and the latter, by a second active stroke of the carriage F, 85 delivered into the transporter B, which meanwhile has returned to the transfer level. In 90 delivering the second section of the matrix line to the transporter, the first or leading section thereof is ejected by the finger F⁹ of the carriage into the receptacle T as shown in Fig. 14. If desired, the second section of the line after casting could be transferred from the transporter back into the stick K before removing the latter from the table H. 95

In composing matrices in the long stick K, the left end wall K⁸ is set in its active 100 position to act as an abutment for that end of the line and the partition K¹⁰ as set in inactive position, the idea being to compose the line of its full final length with the aid of the long scale K¹⁴. Having completed the 105 composition of the line, it is broken up into two sections, one positioned (as if it were an independent line) in the first compartment between the end wall K⁸ and the partition K¹⁰, which latter now is set in active position to act as an abutment for that end of the 110 line section, blank matrices X¹ or Y² being placed at the opposite ends of this first line section. The second section of the line is made up in the same way, being quadded out 115 if necessary to fill up the entire space of the second compartment. It will be understood that, according to this method of composition, matrix lines of any length may be dealt with up to the full capacity of the stick, 120 125 130

namely, 84 ems. Of course, if desired, the stick could be made longer to accommodate lines of even greater length, altho in any case it is preferred that each section of the line be composed on a 42 em basis as herein described.

Having thus described my invention, what I claim is:

1. In a typographical machine, the combination of a line transporter movable vertically from and to a normal line receiving level, a fixed flat horizontally disposed table for supporting a composed matrix line at said level in endwise alinement with the transporter, and manually operated means for transferring the composed line from said table into the transporter.
2. In a typographical machine, the combination with a line transporter movable vertically from and to a normal line receiving level, of a portable hand-stick wherein the matrices are composed in line, means for removably supporting the hand-stick at the line receiving level of the transporter and in endwise alinement therewith, and means for transferring the composed line from the hand-stick into the transporter.
3. In a typographical machine, the combination with a line transporter, of a portable hand-stick wherein the matrices are composed in line, a supporting table, means on the table for removably supporting the hand-stick in endwise alinement with the transporter, and means for transferring the composed line endwise from the hand-stick into the transporter.
4. In a typographical machine, the combination with a line transporter, of a hand-stick wherein the matrices are composed in line, means for supporting the hand-stick in endwise alinement with the transporter, and a manually operated carriage movable in one direction to transfer the matrix line from the hand-stick into the transporter and movable in the opposite direction to transfer said line from the transporter back into the hand-stick.
5. A combination as specified in claim 4, including an intermediate channel for guiding the matrix line in its passage between the hand-stick and transporter.
6. In a typographical machine adapted to handle regular matrices formed with projecting ears or special matrices devoid of projecting ears, the combination with a line transporter, of a hand-stick wherein either the regular or special matrices may be composed in line, means for supporting the hand-stick in endwise alinement with the transporter, and means for transferring the matrix line from the hand-stick into the transporter.
7. A combination as specified in claim 6, wherein the machine is also adapted to handle regular matrices provided with two superposed characters, and characterized by

the fact that the line transporter and hand-stick therein recited are provided with corresponding rails or ledges to support said matrices at an upper level to bring their lower characters into operative position.

8. In a typographical machine, the combination with a line transporter, of a hand-stick wherein the matrices are composed in line, a table for supporting the hand-stick, a device to locate the stick endwise on the table and movable to guide the hand-stick into endwise alinement with the transporter, and means for transferring the composed line from the hand-stick into the transporter.

9. A combination as specified in claim 8, characterized by the fact that the locating device therein recited presents a bar or plate arranged to engage the end walls of a hand-stick and serving to support and guide the matrix line during transfer.

10. In a typographical machine, the combination with a line transporter, of a hand-stick wherein the matrices are composed in line, a table for supporting the hand-stick, means on the table for alining the hand-stick endwise with the transporter, and a reciprocable carriage also mounted on the table for transferring the matrix line from the hand-stick into the transporter.

11. In a typographical machine, the combination with a line transporter, of a hand-stick wherein the matrices are composed in line, a reciprocable transfer carriage including a pair of depending fingers movable into and out of the transporter, and a locating device cooperating with the hand-stick and movable to position the composed line between said transfer fingers.

12. In a typographical machine adapted to handle matrices formed in their edges with transverse recesses for producing the type-bearing portion of the slugs, the combination with a line transporter, of a hand-stick wherein the matrices are composed in line, a pair of blank matrices devoid of recesses arranged at the opposite ends of the stick to close the recesses of the end matrices in the composed line, means for supporting the hand-stick in endwise alinement with the transporter, and means for transferring the composed line with the blank matrices from the hand-stick into the transporter.

13. A combination as specified in claim 12, including detents carried by the hand-stick for locking the blank matrices therein, and means arranged to cooperate with said detents for releasing the blank matrices when the hand-stick is alined with the transporter.

14. In a typographical machine, the combination with a line transporter, of a hand-stick provided with movable end walls and wherein the matrices are composed in line, means for supporting the hand-stick in endwise alinement with the transporter, and means for automatically displacing the end

walls of the hand-stick as it is alined with the transporter preparatory to the transfer of the composed line thereto.

15. A combination as specified in claim 14, including a reciprocable carriage for transferring the composed line from the hand-stick into the transporter, said transfer carriage including a pair of depending fingers between which the composed line is positioned 10 as the hand-stick is alined with the transporter and which fingers effect the displacement of the end walls of the hand-stick.

16. In a typographical machine, the combination with a line transporter, of a hand-stick wherein the matrices are composed in line, a table for supporting the hand-stick, means on the table for alining the hand-stick endwise with the transporter, and means also 20 on the table for holding the hand-stick against displacement in its alined position.

17. A combination as specified in claim 16, characterized by the fact that the hand-stick alining means consists of a pair of fixed banking screws or abutments, and that the holding 25 means therefor consists of a rotary hand-operated wedge for clamping the hand-stick against said abutments.

18. In a typographical machine, the combination with a line transporter, of a hand-stick wherein the matrices are composed in line, a support for the hand-stick arranged at the receiving end of the transporter, a receptacle for the composed line arranged at the opposite end of the transporter, means for 35 transferring the composed line from the hand-stick into the transporter, and means for subsequently transferring the line from the transporter into said receptacle.

19. In a typographical machine, the combination with a line transporter, of a hand-stick wherein the matrices are composed in line, means for supporting the hand-stick in endwise alinement with the transporter, and means for transferring a newly composed 45 line from the hand-stick into the transporter and for simultaneously ejecting a previously composed line from the transporter.

20. In a typographical machine, the combination with a line transporter, of a hand-stick wherein the matrices are composed in line, means for supporting the hand-stick in endwise alinement with the transporter, and a transfer carriage for shifting a newly composed line from the hand-stick into the transporter, said carriage being provided with a 50 pusher for ejecting a previously composed line from the transporter as the newly composed line is shifted into it.

21. In a typographical machine, the combination with a vertically movable power-operated line transporter, of a hand-stick wherein the matrices are composed in line, a reciprocable carriage for transferring the composed line from the hand-stick into the transporter, and horizontally disposed guide-

ways extended directly above the transporter and wherein the carriage is slidably mounted, said guideways being capable of yielding upwardly from their normal position, for the purpose described. 70

22. In a typographical machine, the combination of a vertically movable line transporter normally occupying a position of rest, a hand-stick wherein the matrices are composed in line, said stick comprising a bottom wall, a side wall and two movable end walls, a fixed horizontal supporting table upon 75 which the hand-stick is adapted to rest by its bottom wall, a locating device for the hand-stick in the form of a fore-and-aft slide mounted on the supporting table and having a vertically disposed plate whose flat face is adapted to engage the composed line at the open side of the hand-stick and whose opposite ends are adapted to engage the inner faces of 80 the end walls of the hand-stick, fixed abutments mounted on the table to aline the hand-stick endwise with the line transporter as the hand-stick is moved rearwardly with the fore-and-aft locating slide, a manually operated transfer carriage mounted on the table and presenting a pair of depending fingers 85 arranged to engage the opposite ends of the composed line in the hand-stick, said fingers being adapted to displace the end walls of the hand-stick as the latter is moved rearwardly into alinement with the transporter, and a guiding channel also mounted on the supporting table and thru which the composed line is transferred from the hand-stick into 90 the transporter, said channel comprising a bottom wall adapted to stand flush with the bottom wall of the hand-stick, and two parallel side walls, one adapted to stand flush with the side wall of the hand-stick and the other flush with the vertically disposed plate 95 of the locating device. 100

23. A hand-stick wherein matrices are composed in line, said hand-stick comprising a bottom wall, one side wall, and a pair of end walls, said end walls being movable to active or inactive position, as required. 110

24. A hand-stick as specified in claim 23, characterized by the fact that the end walls are pivotally mounted in the stick so that they may be swung to active and inactive position, and including means for holding the said walls yieldingly in their different positions. 115

25. A hand-stick as specified in claim 23, characterized by the fact that the side wall of the stick is formed with a pair of grooves extending longitudinally thereof, and with an intermediate ledge for supporting regular two-letter matrices at a level above the bottom wall of the stick to bring their lower characters into the operative position. 120

26. A hand-stick as specified in claim 23, including locking means for detachably holding therein a pair of blank matrices adjacent 130

the end walls thereof, for the purpose described.

27. A hand-stick as specified in claim 23, characterized by the fact that the end wall at the exit end of the hand-stick when in active position presents a sloping lower edge whereby to reduce the extent of movement of the end wall when withdrawn from the hand-stick.

10 28. A hand-stick as specified in claim 23, characterized by the fact that the end wall at the exit end of the hand-stick presents a lower edge which conforms in shape to the side wall of the hand-stick, whereby the continuity of said side wall is preserved in the retracted position of the end wall.

29. A hand-stick as specified in claim 23, characterized by the fact that the end walls are pivotally connected to the side wall of the hand stick and that the bottom wall at the opposite edge is provided with upright slotted corner pieces to receive and give support to the end walls when in active position.

30. A hand-stick comprising a continuous bottom wall, one continuous side wall, a pair of end walls, and an intermediate partition plate for dividing the stick into two compartments, said partition plate being movable to and from active position, for the purpose described.

31. A hand-stick as specified in claim 30, equipped with a continuous scale extending longitudinally throughout the length of the stick to indicate the length of a matrix line during composition, and with two additional scales, one for each compartment, to indicate the length of the respective sections of the composed line.

40 32. A hand-stick as specified in claim 30, characterized by the fact that the second compartment, but not the first, is provided with a side wall opposite the said continuous wall.

33. A hand-stick as specified in claim 30, characterized by the fact that the end wall thereof serving the first compartment is capable of movement to and from active position, for the purpose described.

50 34. In a typographical machine, the combination with a vertically movable transporter adapted to carry matrix lines of a given length, of a hand-stick wherein the matrices are composed in line and presenting a continuous bottom wall, a continuous side wall, end walls, one fixed and the other movable, and an intermediate movable partition plate dividing the stick into compartments of said given length, a reciprocable transfer carriage including a pair of depending fingers alined with the transporter, and 60 a locating device arranged to engage the stick and movable therewith to position the sections of the composed line consecutively between the fingers of said carriage, the second section of the composed line being shiftable from the second compartment into the

first compartment of the hand-stick prior to its transfer into the transporter.

35. A combination as specified in claim 34, characterized by the fact that the locating device therein referred to includes a rearwardly movable slide which positions the first section of the composed line between the fingers of the transfer carriage, and that said fingers by such rearward movement of the slide causes the automatic retraction of the movable end wall and movable partition plate.

75 36. A combination as specified in claim 34, including a receptacle arranged beyond the transporter and a pusher associated with the transfer carriage, said pusher being adapted to eject the first section of the composed line from the transporter into said receptacle as the second section thereof is transferred thereinto.

80 37. A combination as specified in claim 34, characterized by the fact that the right-hand finger of the transfer carriage is arranged to be raised and lowered for the purpose described.

85 In testimony whereof, this specification has been duly signed by:

ANTHONY J. STOUGES.
